JAMES DEANS CUMMING, OF COPPER CLIFF, ONTARIO, CANADA.

ACETYLENE-LAMP.

1,225,016.

Specification of Letters Patent.

Patented May 8, 1917.

Application filed August 18, 1916. Serial No. 115,736.

To all whom it may concern:

Be it known that I, JAMES DEANS CUMMING, of the town of Copper Cliff, in the district of Sudbury, in the Province of Ontario, Canada, have invented certain new and useful Improvements in Acetylene - Lamps, of which the following is the specification.

My invention relates to improvements in acetylene lamps, and the object of the invention is to devise a lamp in which the automatic regulation of the amount of gas generated obtains and in which the amount of gas so generated is controlled within narrow limits, in which any acetylene gas that may be generated over and above that required by the flame is conducted by auxiliary passages to the burner and ignited by the flame to consume and not allowed to escape unburned into the atmosphere, in which the lamp is so constructed that the main gas passage is straight from end to end and so that it may be opened at both ends for the purpose of cleaning out dirt and wet ash which tends to accumulate in and clog such passages, in which the main gas passage is so arranged that a portion of its length shall be surrounded by water to cool and condense the steam or vapor that may be in the freshly generated acetylene gas due to the heat developed by the chemical union of the water and calcium carbid. A still further object is to provide a head so formed as to project the flame in a direction approximately horizontal so that a reflector may be used, and further to provide a reflector so supported as to swing around a point coinciding with the focal point of the reflector and it consists essentially of the following arrangement and construction of parts as hereinabove more particularly explained by the following specification.

Figure 1, is a vertical section through my lamp and co-acting parts.

Fig. 2, is an enlarged sectional view through the head portion of the lamp.

Fig. 3, is a plan section on line $x-y$ Fig. 2.

Fig. 4, is a side elevation of the lamp head showing a portion of the reflector supported thereby and in section.

Fig. 5, is a similar view of Fig. 2 showing an alternative form of head.

Fig. 6, is a plan section on line $x'-y'$ Fig. 1.

In the drawings like letters of reference indicate corresponding parts in each figure.

In operating the lamp acetylene gas is

generated by the chemical action of water on calcium carbid, the resulting products being acetylene gas and calcium hydrate or hydrated lime. Calcium hydrate forms a wet ash and acetylene gas is conducted by various means to the burner or burners where it is consumed to provide light. Acetylene gas is an explosive in air or oxygen and when present in sufficient quantities is a danger to the health and comfort of human beings. For this reason it is essential that in acetylene lamps means are provided whereby no gas shall be allowed to escape except through the burner and it is for this purpose my lamp is so constructed as to prevent the escape of gas except as above stated and to insure that gas generated shall be available for the production of light. For the operation of acetylene lamps of this nature it is usually necessary to produce a reflector whereby light may be directed and concentrated where required and it is necessary to provide some simple means whereby this end may be attained.

1 indicates a water tank containing a generating device consisting of a casing 2 forming a carbid chamber 3 and a gas chamber 3^x. The carbid chamber 3 is provided with a head which is preferably in the form of a casting consisting of a circular body 3' and a depending angular flange 3² fitting into the top of the carbid holder casing 2. 3³ indicates a boss extending upwardly from the body 3' and formed with an interior chamber 3⁴ through the upper wall of which an internally threaded orifice 3⁵ extends and through the lower wall of which the orifice 3⁶ formed concentric with the orifice 3⁵ and the internally threaded orifice 3⁷ formed out of a line with the orifice 3⁵ extend. 3⁸ indicates an annular flange extending around the lower end of the orifice 3⁶ for a purpose which will hereinafter appear.

10 indicates a gas pipe for the purpose of conducting the gas from the carbid chamber 3. The lower end of the pipe 10 extends centrally through the orifice 3⁵ and into the orifice 3⁶ in which it is secured. 13 indicates an elbow forming the lamp head. The elbow 13 is provided with a vertical orifice 13^x around the lower end of which depends an annular flange 13' into which the upper end of the pipe 10 extends and is secured. The upper end of the orifice 13^x is provided with a closing plug 13².

On referring to Fig. 2 it will be seen that

the lower end of the orifice 13^x is enlarged so as to form an annular chamber 13³ around the pipe 10. The horizontal portion of the elbow 13 is provided with a central orifice 13⁴ provided with a considerably enlarged outer portion 13⁵. 17 indicates my burner which is secured in the enlarged end 13⁵ of the orifice 13⁴ and is surrounded by a packing gland 13⁶ and packing 13⁷ whereby the joint between the internal periphery of the orifice 13⁵ and the burner is sealed. The body 17^x of the burner 17 is provided with an outwardly tapered portion 17'. From the outer end of this tapered portion extends an annular flange 17². From the inner end of the body 17^x extends an annular flange 17⁴. The inner face of the body 17^x of the burner 17 is provided with an internally threaded orifice 17⁵. 17⁶ indicates a perforation extending through the central portion of the body 17^x into the internally threaded orifice 17⁵. 17⁷ indicates inclined ducts extending from each side of the burner and connecting the space inclosed by the annular flange 17⁴ with the space inclosed by the annular flange 17².

21 indicates a pipe provided with threaded ends screwed respectively into the orifice 17⁵ and orifice 13⁴. 20 indicates a duct connecting the annular space 13³ with the annular space 13⁵ formed by the enlarged portion of the orifice 13⁴ and the pipe 21. 23 indicates a gas pipe which is screwed at its upper end into the orifice 3⁷ of the closing head 3' and opening at its upper end into the chamber 3⁴. The lower end of the pipe 23 depends downwardly into proximity with the bottom of the gas chamber 3^x. The lower end of the pipe 23 is cut at an incline for a purpose which will hereinafter appear.

9 indicates a water separating chamber provided with orifices 9^x and 9' respectively in the upper and lower walls thereof. 9² and 9³ indicate pipes. The lower end of the pipe 9³ is secured to the orifice 9^x and the upper end of the pipe 9² in the orifice 9'. The interior diameters of the pipes 9² and 9³ are greater than the exterior diameter of the pipe 10 thereby forming an annular duct 50 extending upwardly from the chamber 3⁴ to the lower end of the elbow head 13, the chamber 9 being interposed intermediately of the length of such duct. 9⁴ indicates a gland which is threaded on to the upper end of the pipe 9³ and provided with packing 9⁵ to seal the joint between the upper end of the pipe 9³ and the depending flange 13' of the elbow head 13.

It will be noticed that the inner part of the lamp, the body of which is formed by the carbid chamber 3, is not attached to the water tank in any way. The lower portion of the truncated casing 2 forming the gas chamber 3^x is provided with perforations 2³. 2⁴ indicates lugs extending inwardly from

the interior periphery of the casing 2 intermediately of its height. 2⁵ indicates a disk which rests freely upon the lugs 2⁴ and free of the interior face of the casing 2 and is provided with notches 2⁹ sufficiently large to allow the lugs 2⁴ to pass freely therethrough when the notches are brought into alignment with the lugs. 2⁶ indicates an orifice formed in the center of the disk 2⁵. 2⁷ indicates a depending tubular portion extending from the disk 2⁵ and around the orifice 2⁶. The gas pipe 23 extends freely through the tubular member 2⁷ so as to form a surrounding annular space 2⁸.

16 indicates the body of the reflector which is designed to be supported so that the flame 13^x of the burner always remains located in the focal point of the reflector. In order to so support the reflector I have provided the following mechanism.

16' and 16² indicate a pair of studs extending outwardly from the side of the gland 13⁶. 16³ and 16⁴ indicate a pair of brackets secured to the back of the reflector 16 and each provided with arc-shaped slots 16⁵, the arc of which is concentric to the center of the flame 13^x or the focal point of the reflector. The studs 16' and 16² extend through one of the slots 16⁵ as clearly shown in Fig. 4. 16⁶ indicates a set screw which extends through the other slot 16⁵ in the bracket 16⁴ into the internally threaded orifice 16⁷ formed in the gland 16⁶. 16⁸ indicates a vertically disposed slot formed in the reflector through which the flame 13^x extends in all positions of the reflector. It will thus be seen that by forming the slots 16⁵ concentric with the focal center of the reflector, which coincides with the center of illumination of the flame, that it is apparent that at any angle within its range the reflector is reflecting light with a maximum efficiency and the changes of the direction of light rays are effected without changing the direction of the flame itself.

Having described the principal parts involved in my invention I will briefly describe the operation of the same.

The water tank 1 may consist of any suitable container water tight and opening at the top and filled nearly full of water. The carbid container formed by the casing 2 may be of any suitable shape but it is here shown as before described as a truncated cone forming the carbid chamber 3 and gas chamber 3^x. To fill the lamp with calcium carbid the inner part of the lamp is removed, that is to say, the truncated casing 2 and pipes 10, 9², 9³ and connected parts supported by the casing. When these parts are removed they are inverted. The disk 2⁵ is removed by turning it until the notches 2⁹ come opposite the lugs 2⁴ when the disk may be withdrawn. The chamber 3 is then partially filled with calcium carbid 130

and the disk replaced. The casing 2 is then lowered into the tank of water and the pressure of water forces the air trapped under the cone up into the carbide chamber 3 through the pipe 10 and out through the burner hole 17^e. As the air is gradually displaced in this manner by the water passing through the orifices 2³ the water rises in the expansion or gas chamber 3^x past the loosely fitting disk 5 and into contact with the calcium carbide. The volume of acetylene gas is immediately generated which gas forces the water down and away from the carbide and out through the orifices 2³ into the water tank again, the gas partially filling the expansion chamber 3^x. After a short space of time all the air has escaped and the acetylene gas flows through the pipe 10, through the elbow head 13 and out through the hole 17^e and may be ignited to form the main flame. As the gas is consumed the water rises again in the expansion chamber coming again into contact with the calcium carbide so as to generate more gas thereby repeating the operation. The amount of gas formed controls the water level in the expansion chamber 3^x and thereby automatically keeps sufficient gas generated to supply the burner by causing the water to advance or recede as the amount of gas decreases or increases in the expansion chamber 3^x. While the water in the expansion chamber 3^x remains above the lower end of the pipe 23 this pipe and the chamber 3⁴ and pipe 9² will be full of water up to the level of water in the water tank 1. This water surrounds the pipe 10 carrying the hot gas and steam due to generation of acetylene and tends to cool the gas and condense steam, the condensations trickling down the pipe 10 back into the carbide chamber. This cooling and condensing operation has a great value in producing dry gas that burns more efficiently than when hot and moist.

In the ordinary operation of a lamp of this type an excess quantity of gas is suddenly formed due to the wetting of too much carbide which forces the water down and out through the expansion chamber 3^x. If sufficient gas is formed it forces out all water when the gas is enabled to pass out through the orifice 2³ and to escape through the water in the tank 1 and into the atmosphere. To prevent this action the apparatus is provided to conduct any excess gas to the burner where it is consumed. This effect is produced as follows:

Water is forced down and out of the expansion chamber 3^x. When the level is below the lower end of the pipe 23 the gas passes up the pipe 23 through the bypass chamber 3⁴ into the pipe 9² and into the water separating chamber 9. As before described the pipes 23 and 9² are partly

full of water and the gas forces this water up the pipes ahead of it and into the water separating chamber allowing this water to spread out in a thin layer over the bottom of the chamber 9 and through which the gas bubbles up. The chamber 9 must of necessity be placed above the water level in the water tank 1 and be of such a capacity as to be able to contain a greater volume of water than the volume of water that may be forced into it. The excess gas after bubbling up through the water in the chamber 9 passes up through the pipe 9³ and into the elbow 13 through the orifice 20 and then passes out through the ducts 17^e so as to escape and impinge upon the side of the gas flame so as to be ignited thereby and consumed. When all the gas below the end of the pipe 23 is conducted to the burner and consumed the water rises up in the expansion chamber 3^x and seals this passage and all gas then passes through the pipe 10 to the main flame hole 17^e.

From this description it will be seen that I have devised a very simple form of acetylene lamp in which the automatic regulation of the amount of gas generated takes place and in which the amount of gas so generated is controlled within narrow limits, in which the main gas pipe is formed straight from end to end so that when the plug 13² is removed it may be easily cleaned from all wet ash and other deposits which may cling to the interior of the pipe and thus tend to clog the same and in which the reflector and support therefor are provided whereby the light may be directed in any desired direction within certain limits so as to always give in all positions the same maximum lighting power without altering the direction of the flame.

In Fig. 5, I have shown a modification of my construction of burner in which the elbow portion is provided with a burner arm extending in axial alignment with the burner for the purpose of providing a double light, one light extending in the opposite direction from the other, as described in connection with the remaining figures thereby forming a T-head.

In this figure 25 indicates the elbow provided with a burner portion 26 corresponding to that described in connection with Figs. 1, 2 and 3 and a burner arm 27 provided with a central orifice 28 forming an extension of the orifice 13⁴. Such orifice 28 is provided with an enlargement 29 provided with a threaded outer end and into which is secured a burner 30 having a central perforation 31. In the burner 30 it is not necessary to employ inclined ducts corresponding to the inclined ducts 17^e hereinbefore described, as these are of sufficient capacity to take care of all excess gas.

In Fig. 1, the lower end of the pipe 23

is shown inclined. This is to allow the excess gas to gradually feed into the pipe 23 and not to pass into it with a sudden rush which would be the case if the pipe were 5 cut horizontally carrying the water up with it.

The flange 3^s hereinbefore described is provided so that any moisture, dust or wet ash, is prevented from passing into and 10 clogging the gas passage.

What I claim as my invention is:

1. In an acetylene gas lamp, the combination with a submerged generating chamber and a gas burner head, of a gas duct extending vertically from the generator to the burner head, an excess gas duct extending 15 between the generating chamber and burner head and surrounding the main duct whereby the excess gas in the generator, when 20 its volume and pressure are sufficient to unseal the excess gas tube, will be conducted

to the burner to be consumed thereat, and a water separating and expansion chamber located in the excess duct above the water submerging the generator.

2. An acetylene burner and generator comprising a tapering receptacle provided with upper and lower compartments, a head for the receptacle, a pipe depending from said head to the lower compartment, a disk 25 separating the compartments having a depending sleeve encircling the pipe and spaced therefrom, a burner, a pipe therefrom extending through said head, and a duct encircling the latter pipe and spaced 30 therefrom terminating within said head, said head having a communicating passage between the depending pipe and the duct.

JAMES DEANS CUMMING.
